United States Patent Office.

JAMES H. MCKERNAN, OF INDIANAPOLIS, INDIANA.

Letters Patent No. 102,954, dated May 10, 1870.

IMPROVEMENT IN MODE OF OPERATING SHUTTERS FOR HATCHWAYS.

The Schedule referred to in these Letters Patent and making part of the same.

I, JAMES H. MCKERNAN, of Indianapolis, in the county of Marion and State of Indiana, have invented certain Improvements in the Mode of Operating the Shutters, Closing the Stairways, Hatchways, and Corridors of Buildings, of which the following is a specification.

Nature and Objects of the Invention.

My invention relates to the construction and mode of operating horizontal shutters over stairways and hatchways, and vertical shutters across the corridors of buildings; and

It consists in the arrangement of chains or cords attached to the shutters in such a manner that said cords, being wound upon drums on a vertical shaft situated in proper position, and extending throughout any desired number of stories of the building, so that the shutters of either stairways, hatchways, or corridors of all the floors may be operated simultaneously, or each one may be operated separately, as may be desired, the object being to provide a ready means of closing the openings in the several floors and halls or corridors, both as a preventive to the loss of life and the extension of fires.

Description of the Accompanying Drawings.

Figure 1 is a vertical section through a building, taken transversely of the corridor in which the stair and hatchways in the several floors, and also the corridors are furnished with shutters that are operated by means of the device embodying my invention.

Figure 2 is a horizontal section or plan view of a floor of a building, showing a stairway and corridor furnished with shutters that are operated by means of my device.

Figure 3 is a detail view of the horizontal shutter for closing stair and hatchways, showing more clearly the means employed for operating them.

Figure 4 is a vertical transverse view of the corridor of a building, showing the shutter for closing it, and the arrangement of the cords and pulleys for operating the shutter.

Figure 5 is a detail view of the drum and a portion of the vertical shaft by means of which the cords or chains are wound and the shutters are operated.

Figure 6 is an inverted view of the shutters employed to cover the stair and hatchways.

Figures 7 and 8 are detail views of the trucks on which the shutters are supported and run.

General Description.

The horizontal shutters A are made of sheet metal or other indestructible material, on a frame of angle-iron, b, and are furnished with trucks or rollers B on

the under side, and horizontal friction-rollers, e, in the ends, so arranged that the shutters will move freely with slight force applied to the wheel-cranks G.

The shutters are made as much longer than the opening as is necessary to provide room to attach the rollers B, so that they will run outside of the opening.

The shutters may be let into a recess in the floor, so as to be flush with the upper surface thereof, and should be made to fit to the edges of the recess sufficiently close to prevent a draught of air through them when closed.

To operate the shutters A I attach a cord, O, to the angle-iron at the rear edge of the shutter, and carry it forward around the sheave or pulley D, and from thence to one side of drum E on the vertical shaft F; also, a cord, C, to the angle-iron at the front edge of the shutter, which passes over the sheave D' and under pulley d, to bring it in proper position to the opposite side of drum E. When necessary to turn angles, as shown in figs. 2 and 3, the cords are taken around horizontal pulleys H.

The sheaves D D' are so situated and arranged that they, and also the cords C C', are protected from exposure and liability to injury by being walked over.

The vertical shaft F extends through any desired number of stories of the building, and is furnished with crank-wheels G, by which to turn it either to the right or left, as may be desired, to open or close the shutters, and is made in sections that are coupled together at each floor by a sliding or adjustable coupling, J, so arranged that the sections of the shaft in any story may be coupled with or uncoupled from the section above or below it, so that the shutters of either floor or story may be operated separately, or the shutters of all the floors may be operated simultaneously, as may be desired.

I are guide-arms, attached to a nut, a, working freely on a screw-thread cut on the shaft F. These arms have eyes at their outer ends through which the cords C C' pass, and are designed to lay the cords properly on the drums E as they are wound up, either in opening or closing the shutter, and also to prevent the cords from slipping off the drum in case they become slack.

The anti-friction rollers B are constructed and arranged in nests of five each, as shown in figs. 7 and 8, and are attached to the corners of the shutters A, as shown in fig. 6. Similar trucks are attached to the corners of the bottom edge of the vertical shutters K.

Vertical shutters K, arranged to close the corridors or passages through buildings, may be operated in a similar manner, as shown in fig. 4.

The advantages claimed for the construction, arrangement, mode of operating the shutters of stair and

hatchways and corridors of buildings as herein described are, that the shutters being arranged so as to be very conveniently closed, either singly or on any floor, or throughout the entire building simultaneously, as may be desired, the hatches are more likely to be closed after being used during the day, thereby avoiding injury or loss of life by persons falling through them, as too often occurs, and also serving as a ready means of shutting off draughts of air through the buildings in case of fire, thereby preventing loss of property, besides being a great security against the spread of fires, by having the stairs, hatches, and corridors closed at night, as the labor of closing one is little less than closing all the stairs, hatches, and corridors in a building.

Claims.

I claim as my invention—

1. The arrangement of the cords or chains C C', attached to the shutters A and K, in combination with the sheaves or pulleys D D', d, and H, drum E, and vertical shaft F, substantially as and for the purpose set forth.

2. The vertical shaft F, provided with the drum E, crank-wheels G, coupling J, and guide-arms I, attached to a nut a, all constructed and arranged substantially as and for the purpose set forth.

JAMES H. MCKERNAN.
